UNITED STATES PATENT OFFICE.

ROBERT EMMET KEOUGH, OF MONTREAL, QUEBEC, CANADA, ASSIGNOR TO THE AMERICAN FORK & HOE COMPANY, OF CLEVELAND, OHIO, A CORPORATION OF OHIO.

RAIL ANCHOR.

Application filed March 2, 1927. Serial No. 171,953.

My invention relates to rail anti-creeping devices and more particularly it relates to such a device comprising a rail gripping member and a buffer plate disposed between 5 adjacent ties.

One of the objects of my invention resides in the provision of an improved anti-creeping device for rails employing a buffer plate and a rail gripping member, and wherein the 10 rail gripping member may cooperate with the buffer plate so as to efficiently grip the rail base and prevent the rail from creeping in either direction when trains pass over the rail in either direction.

Another object of my invention is to provide 15 an anti-creeping device for rails adapted to support a rail gripping member wholly below the rail base flange.

Another object of my invention is to provide 20 an anti-creeping device for rails comprising a rail gripping member and a buffer member and wherein the buffer member may have a portion adapted to grip the rail.

Another object of my invention resides in 25 the provision of an improved anti-creeping device for rails which is durable and serviceable in use, economical to manufacture, and which may be readily applied to the rail by a simple operation.

These and other objects of my invention 30 and the invention itself will become apparent from reference to the following description of certain embodiments thereof and in which description reference will be had to the accompanying drawings forming a part of this 35 specification.

Referring to the drawings:

Fig. 1 shows a top plan view of a fragment 40 of a rail and a pair of rail ties embodying my invention;

Fig. 2 shows a side elevational view of the same;

Fig. 3 shows a transverse sectional view taken on the line 3—3 of Fig. 1;

Fig. 4 shows a fragmentary perspective view 45 of the foregoing embodiment illustrating the gripping action of the anchor member on the rail base flange;

Fig. 5 shows a top plan view of a fragment 50 of a rail and a pair of adjacent rail ties embodying a modified form of my invention;

Fig. 6 shows a side elevational view of the same; and

Fig. 7 shows a transverse sectional view 55 taken on the line 7—7 of Fig. 5.

Referring to the drawings and referring first to the preferred embodiment of my invention illustrated in Figs. 1, 2, 3, and 4 of the drawings, wherein like parts are designated by like reference characters, at 10, I 60 show a railroad rail of the conventional form having a rail head flange 11, a rail base flange 12, and an interconnecting web 13. At 14 and 15, I show two railroad ties preferably spaced apart the standard distance and 65 having rail chairs 16 and 17 on which the rail base flange rests in supporting the rail.

The anti-creeping device preferably comprises a buffer plate, generally indicated at 20, having an integral depressed central base 70 portion 21 preferably disposed equi-distant from the ties. The base portion is preferably provided with a pair of upstanding rearwardly inclined notched flanges 23 and 24, forming an integral part of the buffer 75 plate. Extending upwardly and longitudinally of the rail are a pair of wings 25 and 26, preferably bent at 27 and 28 into the horizontal plane of the rail base flange and extending from the top surface of the ties 80 laterally of the rails and out of contact therewith and integrally joined with the base portion 21 of the substantially U-shaped rail anchor element 22 the wings 25 and 26 being provided with apertures 29 and 30 adjacent 85 their ends through which spikes 31 are driven to retain the buffer plate 20 to the ties.

Flanges 23 and 24 are obliquely notched at 32 and 33, to produce aligned slots adapted to embrace a rail base flange edge 34. A co- 90 operative rail gripping member comprising a one-piece flat resilient steel shank 40 having an upturned hooked end 41 adapted to be projected between parallel flanges 23 and 24 and the base 22 of the U-shaped anchor element and adapted to effect engagement with the rail base flange edge at 43, with an intermediate portion flexed downwardly at 42 from a point of contact with the rail flange 100 at 44 out of contact with the rail base flange and pressed upwardly into contact with the bottom of the rail base flange adjacent the opposite edges. The shank of the member 35 is bent back upon itself to form a loop 48 adapted to be wedged between the bottom of the rail base flange and the platform or floor 57 of the buffer plate 20 by virtue of the resiliency of the loop, thereby causing the notched U-shaped anchor element 22 to exert a downward inward pull on the element 22 to cause 110

it to move inwardly toward the middle of the rail, and simultaneously effecting a lateral drawing action on the hooked end 41 of the anchor clamping the same into tight engagement with the edge of the rail base flange at 43 to effectively secure the gripping member onto the rail base flange. The end portion of the loop is bent upwardly at 46 and contacts with the intermediate downwardly flexed shank portion at a point indicated at 47, and tends to flex the shank upwardly to straighten the same while effectively retaining the gripping member on the rail.

The rail gripping member 35 is preferably 15 of a width to fit between the impact flanges 23 and 24 so that the slight clearance between the sides of the flanges and the edges of the gripping member is only sufficient to permit a slight tilting or rocking of the gripping member in a longitudinal direction relative to the rail, thereby relieving unnecessary stresses on the member.

The gripper member may be applied to the rail base flange between the impact flanges by 25 a force exerted on the looped end by a tool, such as a maul, which drives the hooked end of the anchor across the rail base flange and at the same time partially straightens the curved portion of the shank until the hooked end of the anchor snaps onto the edge of the rail base flange; the intermediate portion of the shank will now flex downwardly away from the bottom face of the rail base flange considering the hooked end to securely grip 30 the edge of the rail base flange, while the looped end will be wedged in the U-shaped plate 20 and draw the edges of the notches 32 and 33 into gripping engagement with the upper and lower faces of the rail base flange.

40 The anchor plate 20 and the rail and anchor element 35 are preferably disposed equi-distant between the rail ties and preferably positioned beneath the rail base flange.

Referring to Figs. 5, 6 and 7, I have illustrated another embodiment of my invention 45 which is similar in operation to the foregoing embodiment. However, in this embodiment of my invention, I contemplate providing a buffer plate 20' with a pair of downwardly 50 extending flanges 23' and 24'. Between the flanges, I dispose a U-shaped member 70 comprising a portion of the rail gripping anchor, the sides 71 and 72 of which are notched at 32' and 33' into which the rail base flange extends. I dispose a rail gripping shank 35' 55 forming a second portion of the rail gripper similar in construction to the rail gripping member 35 of the foregoing embodiment, whereby, when applied to the rail in this manner, the flanges 23' and 24' act as impact receiving members for the lower portions of the sides of the U-shaped member 70 and overcome tendency of the rail anchor to creep or move longitudinally on the rail base flange. 60 Such a buffer plate as illustrated in this form

of the invention is particularly adaptable to permit the rail anchor shank 35' and the U-shaped member 70 to be removed from the rail base flange without necessitating removal of the buffer plate 20' from the ties.

70 While I do not wish to limit my invention to the specific form of the rail gripping member 35 and 35' and U-shaped notched retainers 22 and 70, respectively, and which are substantially of the form illustrated, described 75 and claimed in the prior patent to Francis W. Cooper, No. 1,618,576, dated February 22, 1927, except that the said patent does not disclose anything corresponding to the winged buffer element of the present application. I 80 contemplate employing various types of rail gripping members adaptable for practical use in connection with the buffer plate 20 and 20'.

In the embodiments of my invention herein described, it is to be noted that engagement is had between the portions of the element secured by spikes to the adjacent ties, and the U-shaped notched elements of the rail anchor, substantially as shown in the said Cooper patent, below the level of the rail base flange. 90 This is very important as in other constructions wherein engagement is had at the level of the rail base flange or above it, not nearly so efficient a gripping action will be had responsive to the longitudinal movements of the rail in both directions, which movements are most efficiently restrained, with resilience of restraint by the mechanisms described herein by virtue of the engagement below the rail base flange. Such engagement accomplishes 95 a tendency toward tilting of the U-shaped body relative to the rail base and causes the jaws formed in the notched plate flanges to bite more firmly the rail base flange to thus secure a better grip thereupon commensurable with the amount of the tendency toward longitudinal movement affected by the rails.

100 Having thus described my invention in certain specific embodiments, I am aware that numerous and extensive departures may be 110 made from the embodiments herein illustrated and described but without departing from the spirit and scope of my invention.

I claim:

1. In a rail anchor, the combination with a 115 rail gripping mechanism disposed below the rail base flanges and gripping the rail in the lateral portions of the flanges and comprising a downwardly extending portion below one of the rail base flanges and laterally extending wings rigidly joined to the downwardly extending portion at a substantial distance below the rail base flange, adapted to be secured to the adjoining pair of rail supporting ties to prevent lateral movement 120 of the anchor in its lowermost portion.

125 2. In a rail anchor, a rail gripping mechanism adapted to be secured to the rail base flanges and comprising a notched jaw adapted to receive within its notch a projecting 130

- lateral portion of a rail base flange and having a portion integral therewith depending therefrom to a substantial distance below the flange and means having a laterally extending portion adapted to be spiked to an adjoining rail supporting tie rigidly joined to a lower part of said depending portion. 5
3. In a rail anchor, a rail gripping mechanism adapted to be secured to the rail base flanges and comprising a notched jaw adapted to receive within its notch a projecting lateral portion of a rail base flange and having a portion integral therewith depending therefrom to a substantial distance below the flange and means having a laterally extending portion adapted to be spiked to an adjoining rail supporting tie adapted to hold the lower part of the said depending portion substantially against lateral movement. 15
4. In a rail anti-creeper, the combination with a U-shaped body, having notched arms adapted to hook onto one edge of a rail base and a holding anchor member adapted to pass through the body and hookingly engage the opposite edge of the rail base, the holding member being formed to engage towards its ends with the under surface of a rail base and spaced intermediate its ends from the rail base and means adapted to take the lateral thrusts imparted to the body comprising laterally extending arms adapted to be spiked to the rail supporting ties in portions remote from the body and to directly hold portions of the body disposed below the rail base from lateral movement relative to said ties. 25
5. In an anti-creeper for railroad rails, in combination with a rail anchor comprising a body part and a holding part, said body part comprising a portion of substantially U-shaped form with aligned notches through its arms and having an intermediate portion disposed below the rail base, said holding member comprising a bent shank and a loop at one end of the shank adapted for compression between the body seat and a rail base, and a hooked end for the holding member adapted to be projected upwardly upon compression of the loop against the rail and to hookingly engage the edge of the rail base opposite said body, and a holding element adapted to be spiked at its ends to different rail supporting ties and having a depressed intermediate portion adapted to hold portions of the body disposed below the level of the rail base against substantial lateral movement. 50
6. In an anti-creeper for railroad rails, in combination with a two-piece rail anchor, comprising a wedge-shaped spring member having a hooked end and a U-shaped body having parallel arms with aligned notches adapted to embrace one flange of a rail base, said spring member projected between the arms of the body and engageable with the intermediate seat thereof, and adapted to be resiliently compressed between the said seat and the bottom surface of the rail base, and means comprising a sheet metal strip adapted to rigidly hold the body in its lower portion against lateral movement, said strip adapted to have its ends perforated to receive securing spikes projected into different rail supporting ties and an intermediate depressed portion for holding the said lower portion of the body. 60
7. In a rail anti-creeper, the combination with a buffer plate comprising a body having an intermediate depressed portion, a pair of parallel flanges extending upwardly therefrom, a pair of aligned notches in the parallel flanges adapted to receive a portion of a rail base flange and grip the same, and a looped holding member passed between the said parallel flanges, the intermediate depressed portion of the plate, and the bottom of the rail base, and to hookingly engage the edge of the rail base opposite said notched flanges, and integral means extending between each of a pair of adjacent rail supporting ties and spiked rigidly thereto, adapted to restrain lower portions of the body flanges against movement in either direction and to effect tilting of the body to increase the grip of the body upon the rail flange. 65
- In testimony whereof I hereunto affix my signature this 16th day of Feb., 1927.
- ROBERT EMMET KEOUGH.
